UNITED STATES PATENT OFFICE

HARRY W. THATCHER, OF HOPEDALE, MASSACHUSETTS, ASSIGNOR TO DRAPER CORPORATION, OF HOPEDALE, MASSACHUSETTS, A CORPORATION OF MAINE

SHED FORMING MECHANISM FOR LOOMS

Application filed May 8, 1931. Serial No. 535,935.

This invention relates to shed forming mechanism for a loom of that type in which the harness frames are moved by a cone and in which the cone is operated by a crank motion.

The object of the invention is to provide a construction in this type of shed forming mechanism which shall insure the same position for the crossing of the shed at all times.

10 The object of the invention is further to secure in this type of shed forming mechanism a construction in which the crossing of the shed shall take place at the same period in the cycle of a loom operation during the 15 oscillation of the cone in both directions.

These and other objects and features of the invention will appear more fully from the accompanying description and drawings and will be particularly pointed out in the claims.

20 As the general construction and operation of this type of shed forming mechanism and the means for operating it in timed relation to the other mechanisms of the loom are all well known and familiar to those skilled in 25 the art, it is only necessary here to illustrate and describe such portion of a loom and shed forming mechanism as is necessary to a disclosure of the present invention.

30 In the drawings:

Fig. 1 is a front elevation of a portion of a loom arch, harness frames and connected elements including a preferred form of mechanism embodying the invention for operating the harness frames.

35 Fig. 2 is a view on a larger scale of the construction shown in Fig. 1 looking at the left-hand side of the loom.

40 Fig. 3 is a view in detail of a conoidal actuator showing the principle of construction employed.

A portion of an ordinary type of loom is shown comprising the side frame 1 and the arch 2 mounted on the side frames and extending across the loom. The usual crank 45 shaft for operating the lay is indicated at 3. The shed forming mechanism comprises the usual harness frames, a portion of one of which is shown at 4. Any number of these harness frames may be employed and, as 50 illustrative thereof, provision is shown for

twelve such frames. These harness frames are here assumed to be lowered in the usual manner by springs, not shown, extending from the bottom of each harness frame to the base of the loom or its support, while 55 the raising and lowering of the frames in opposition to these springs is effected by the cone harness mechanism.

A cone harness mechanism is a useful type because it is adapted to the control of a large 60 number of harness frames with a very simple operating mechanism and because it provides for the increase in shed opening required of the harness frames from front to rear to correspond with the divergence of the 65 sheets of warps forming the shed. The main element of this mechanism is usually operated by a crank to effect the required oscillatory movement. Such a crank mechanism is highly desirable for this purpose, 70 but it essentially involves a serious error in the movements of the harness frames. In order that the filling may be beaten in under precisely the same conditions at all times, it is essential that the harness frames should 75 come to the same central closed shed position each time the shed is closed and this closed position should correspond with the position of the lay at front center or at the conclusion of the beat-up. But with a crank mechanism, as heretofore employed, the mid position of the harness frames or the position of the closing of the shed does not correspond with the mid positions of the crank 80 in its arcs of movement between the extreme upper and lower positions of the frames or 85 the extreme open positions of the shed.

The present invention, by means of a novel principle of construction and operation, enables the crank operating mechanism to be 90 retained and this error in the closing of the shed to be eliminated.

The element here employed corresponding to the usual cone is not of a true cone form and is herein termed a "conoidal actuator". 95 In the preferred construction illustrated, this conoidal actuator presents two similar sections 5 and 6 symmetrically disposed with respect to the axis of oscillation. These sections are each shown as composed of suita- 100

ble material such as metal having respectively inwardly projecting webs 7 and 8 slotted and adjustably secured by bolts 9 to radial flanges 10 extending from a hub 11 adjustably secured by set screws 12 to the axial shaft 13. This shaft is journaled in brackets 14 secured to the front and rear portions 15 of the transverse member of the loom arch. The shaft 13, and consequently with it the conoidal actuator, is oscillated by a crank mechanism. In the construction illustrated the crank pin 16 is carried on an elliptical gear 17 journaled at 18 in the side frame and this gear is driven by a cooperating elliptical gear 19 on the shaft 3, thus giving a variable movement frequently desired in the opening and closing of the shed. An arm 20 is secured to and extends laterally from the end of the shaft 13. This arm is connected by a pitman 21 to the crank pin 16. Suitable adjustments for lengthening and positioning of the pitman and suitable universal joint connections at the ends of the pitman are provided. As illustrated, the pitman at its upper end has threaded thereon a bifurcated socket 22 held in place by a lock nut 23. In this socket is journaled at 24 a link member 25 which in turn is journaled on a stud 26 adjustably mounted in a slot 27 extending longitudinally of the arm 20. At its lower end the pitman is shown as having threaded thereon a similar bifurcated socket member 28 held in position by a nut 29 and a similar link member 30 is journaled in the socket member 28 at 31 and is in turn journaled on the crank pin 16.

The several harness frames are operated by suitable flexible connectors extending from the harness frames over suitably positioned idler rollers to the conoidal actuator in the usual manner. The connector from each harness frame extends to the one section or the other of the conoidal actuator according to the shed pattern desired, all in a usual and familiar manner. Two sets of idler rolls are shown supported on shafts 32 and 33 mounted in brackets 34 secured to the front and rear portions 15 of the loom arch so that these shafts extend parallel with the shaft 13. A series of idler rollers 35 are journaled on these shafts, one for each harness frame on each shaft. At the end of the arch opposite the conoidal actuator another shaft 36 is mounted in brackets 37 also secured to the members 15 and extending parallel with the shafts 13, 32 and 33. This shaft 36 is journaled in bearings 38 mounted to slide transversely of the loom in the brackets 37 and adjusted and held in adjusted position by set screws 39, thus enabling slack to be taken up in the connectors. This shaft 36 also carries a series of idler rolls 40, one for each harness frame. Two sets of flexible connectors are shown and the arrangements of the remaining sets will be obvious. In the first set one

end of the flexible connector 41 extends along the first groove at the front of the section 5 of the conoidal actuator and is secured to the actuator by engagement with a hook 42 hooked into the edge of the section 6 of the actuator. This connector extends around the front roll 40 on the shaft 36 and then is divided into two portions, one of which 43 extends around the first roll 35 on the shaft 32 and is secured at 44 to the harness frame 4, while the other 45 extends around the first roll 35 on the shaft 33 and is secured at 46 to the harness frame 4. The next following harness frame is connected so as to move oppositely to the frame 4. Consequently its flexible connector 47 extends along the second groove in the section 6 of the conoidal actuator and is secured at its end by a hook 48 to the edge of the section 5. This connector 47 then extends around the second roller 40 on the shaft 38 and then is divided, passes around rollers 35 on the shafts 32 and 33, and extends at 49 to its harness frame. The several connectors are shown as made in sections hooked or otherwise secured together and may be of any usual or desired construction.

The taper of the conoidal actuator is arranged as usual so that the several harness frames shall be raised and lowered thereby an increasing amount beginning at the front of the loom to cause the frames when in open shed position to correspond with the slope of the warp sheets.

It will be seen that the shed will be open and the several frames in their highest or lowest positions when the crank pin 16 is in either its uppermost or its lowermost position and consequently the arm 20 is in its uppermost or lowermost position. But owing to the inherent character of a crank motion, it will be seen that the mid positions of the arm 20 will not correspond with the mid positions in its arcs of movement of the crank pin 30 and consequently the shed will be closed at different periods in the cycle of the loom operation.

In this invention this error in the operation of the shed forming mechanism is corrected to cause the shed to close always at the same period in the cycle of the loom operation and when the crank pin is at each of its mid positions. For this purpose the curvature of the several grooves in the conoidal actuator along which the flexible connectors rest are shaped so that when the crank pin moves 90° in either direction from its mid position, that is, through half of the arc of movement between its extreme upper and lower positions, equal amounts of each connector are wound upon or unwound from the actuator, thus giving equal amounts of movement to the several harness frames for each 90° of movement of the crank pin. This is most readily accomplished by laying off the curvature of the several zonal grooves in the sections of the

conoidal actuator graphically. During the periods the crank pin is moving between its mid positions and its uppermost position, the conoidal actuator will move through a greater arc than during the periods when the crank pin is moving between its mid positions and its lowermost position, and consequently to allow the same length of connector to be wound or unwound in both cases, the radius of curvature of the grooves must be varied to the extent required to effect this result.

Fig. 3 illustrates diagrammatically a layout for the conoidal actuator. The axis of rotation of the actuator is at 50. The upper half of the figure is shown offset to the left of the lower half for convenience in making a large scale drawing; but it is to be understood, of course, that 50 represents the common axis of the shaft 13, also shown in two offset sections. Laying out the curvature of the grooves 51 to 62 so that the radius of curvature with respect to the axis 50 increases from the left to the right in the section 5, and correspondingly from the right to the left in the section 6, so as to give an equal amount of winding or unwinding movement of the connectors during the 90° of movement of the crank pin, it is found that the curves approximate those shown in the drawings and that these curves approximate very closely circular arcs whose centers are offset from the axis 50 and whose radii of course increase as the grooves are further from the front. It is found also that immediately successive curves are approximately concentric so that it is not necessary to have separate centers for each curve. For example, it is found that for the grooves 51 and 52 the radii thereof may have a common center 63, for the grooves 53 and 54 a common center 64, for the grooves 55 and 56 a common center 65, for the grooves 57, 58 and 59 a common center 66, and for the grooves 60, 61 and 62 a common center 67, with a similar arrangement for the opposite section 6. The exceedingly close approximation obtained by the use of grooves formed on circular arcs and having the centers arranged as described enables the sections of the conoidal actuator readily to be constructed mechanically and reduces the cost of manufacture.

Each section of the conoidal actuator is thus formed on the same principle and each is preferably of precisely the same construction so that the sections are interchangeable. It will be seen that referring the arc of curvature of each groove with respect to the axis of oscillation the radii progressively increase from one edge of the section to the other to secure the desired result. It will also be seen that with a circular arc of curvature of each groove that the centers of these circular arcs are all located at the same side of the axis of oscillation and at varying degrees of eccentricity and with the center of each arc

of each groove no nearer the axis than the center of the arc of the next adjacent groove toward the smaller end of the section.

There is thus produced a very simple construction of actuator for the ordinary type of cone harness mechanism which eliminates the inaccuracy heretofore inherent in this very useful mechanism and enables its adaptation with accuracy to any number of harness frames and insures the closing of the shed by the bringing of all the harness frames to the same central closed shed position when the crank is in either mid position and consequently in proper timed relation to the cycle of loom operation.

Having thus described the invention, what is claimed as new, and desired to be secured by Letters Patent, is:

1. Shed forming mechanism for looms comprising a plurality of harness frames, a conoidal actuator having parallel zonal grooves, a crank and connections therefrom to the actuator for oscillating the actuator on its axis with each revolution of the crank, and flexible connectors extending from each harness frame along corresponding grooves of the actuator and secured thereto in which the radii of each of said grooves with respect to the axis of oscillation progressively increase in length throughout the arc of oscillation to cause equal amounts of each connector to be wound upon or unwound from the actuator as the crank moves 90° from or to its mid positions, thereby to bring all the harness frames to the same central closed shed position when the crank is in either mid position.

2. Shed forming mechanism for looms comprising a plurality of harness frames, a conoidal actuator having parallel zonal grooves, a crank and connections therefrom to the actuator for oscillating the actuator on its axis with each revolution of the crank, and flexible connectors extending from each harness frame along corresponding grooves of the actuator and secured thereto in which each of said grooves is formed on a circular arc having its center located eccentric the axis of oscillation and its radius proportioned to cause equal amounts of each connector to be wound upon or unwound from the actuator as the crank moves 90° from or to its mid positions, thereby to bring all the harness frames to the same central closed shed position when the crank is in either mid position.

3. Shed forming mechanism for looms comprising a plurality of harness frames, a conoidal actuator presenting two similar sections symmetrically disposed with respect to its axis with each section having parallel zonal grooves, a crank and connections therefrom to the actuator for oscillating the actuator on its axis with each revolution of the crank, and flexible connectors extending

- from each harness frame along corresponding grooves of one or the other of the sections of the actuator and secured thereto and in which the radii of each of said grooves with respect to the axis of oscillation progressively increase in length throughout the arc of oscillation to cause equal amounts of each connector to be wound upon or unwound from the actuator as the crank moves 90° from or to its mid positions, thereby to bring all the harness frames to the same central closed shed position when the crank is in either mid position.
4. Shed forming mechanism for looms comprising a plurality of harness frames, a conoidal actuator presenting two similar sections symmetrically disposed with respect to its axis with each section having parallel zonal grooves, a crank and connections therefrom to the actuator for oscillating the actuator on its axis with each revolution of the crank, and flexible connectors extending from each harness frame along corresponding grooves of one or the other of the sections of the actuator and secured thereto in which each of said grooves is formed on a circular arc having its center located eccentric the axis of oscillation and its radius proportioned to cause equal amounts of each connector to be wound upon or unwound from the actuator as the crank moves 90° from or to its mid positions, thereby to bring all the harness frames to the same central closed shed position when the crank is in either mid position.
5. An oscillatory actuator section for a loom shed forming mechanism having a conoidal surface provided with parallel zonal grooves to receive flexible connectors from the harness frames in which each of said grooves lies on a curve, the radii of which with respect to the axis of oscillation progressively increase from one edge of the section to the other.
6. An oscillatory actuator section for a loom shed forming mechanism having a conoidal surface provided with parallel zonal grooves to receive flexible connectors from the harness frames in which each of said grooves lies on a circular arc having its center eccentric the axis of oscillation of the actuator section with the said centers located at the same side of the axis of oscillation and at varying distances therefrom and with the center of each arc no nearer the said axis than the center of the arc of the next adjacent groove toward the smaller end of the section.

In testimony whereof, I have signed my name to this specification.

HARRY W. THATCHER.
